Application May 22, 1952, Serial No. 19,832

Term of patent 7 years

(Cl. D44—1)

To all whom it may concern:

Be it known that I, Milton F. Klein, a citizen of the United States, residing at Glens Falls, county of Warren, State of New York, have invented a new, original, and ornamental Design for a Meat Carving Board with Hinged Sections, of which the following is a specification, reference being had to the accompanying drawing, forming a part hereof.

Fig. 1 is a plan view of a meat carving board embodying my new design with the hinged sections open;

Fig. 2 is a sectional view thereof taken on line 2—2 of Fig. 1;

Fig. 3 is a plan view of the meat carving board with the hinged sections closed;

Fig. 4 is a sectional view thereof on line 4—4 of Fig. 3;

Fig. 5 is a sectional view thereof on line 5—5 of Fig. 3, and

Fig. 6 is a perspective view of the meat carving board with the hinged cover closed.

I claim:

The ornamental design for a meat carving board with hinged sections, as shown.

MILTON F. KLEIN.
